Inventor.

Riley Bratton.

United States Patent Office.

RILEY BRATTON, OF OSKALOOSA, IOWA.

Letters Patent No. 67,628, dated August 13, 1867.

IMPROVEMENT IN WAGON-BEDS.

The Schedule referred to in these Letters Patent and making part of the same.

TO ALL WHOM IT MAY CONCERN:

Be it known that I, RILEY BRATTON, of Oskaloosa, in the county of Mahaska, and State of Iowa, have invented a new Improvement in Wagon-Beds; and I do hereby declare that the following is a full and exact description thereof, reference being had to the accompanying drawings, and to the letters of reference marked thereon.

The nature of my invention consists in metallic standards attached to a wagon-bed of the ordinary form, said standards with hooks on the lower ends hooking into staples in the bottom bars of the bed.

Figure 1 represents the wagon-bed complete when put together.

Figure 2 represents one of the side-boards detached.

Figure 3 represents one of the bottom bars of the wagon-bed detached.

a a a represent the metallic standards. *b b* in fig. 1 represent the apertures in which the hooked ends of the standards are placed. *c c* in fig. 3 represent metallic staples fastened to the bottom bars. *d d d d* represent the bottom bars. *e e* represent plates of metal covering the staples *c c*. These plates have the apertures *b b* through them.

The hooked ends of the metallic standards *a a a* are put into the apertures *b b*, and the lower ends hooked into the staples *c c*. The side boards are then straightened up and the end gates *ff* put in their places, and the front end gate fastened with the hooks *g g*, and the bed is then complete. In the drawing, black denotes wood and red denotes metal.

What I claim as my invention, and desire to secure by Letters Patent, is—

An improvement on ordinary wagon-beds as herein described, consisting of metallic standards with hooked ends fastening in staples, and claim the peculiar form of standards and location of staples as my invention, by which a wagon-bed may be easily and quickly taken apart and put together.

RILEY BRATTON.
